DESIGN FOR A REFLECTOR UNIT OR THE LIKE

John C. Haggart, Jr., Westfield, N. J., assignor to
Signal Service Corporation, a corporation of
Delaware

Application January 16, 1941, Serial No. 98,130

Term of patent 14 years

To all whom it may concern:

Be it known that I, John C. Haggart, Jr., a citizen of the United States and a resident of Westfield, in the county of Union and State of New Jersey, have invented a new, original, and ornamental Design for a Reflector Unit or the like, of which the following is a specification, reference being had to the accompanying drawing, forming part thereof, wherein:

Fig. 1 is a plan view of a reflector unit showing my new design;

Fig. 2 is a side elevation of the same; and

Fig. 3 is an end elevation of the same.

I claim:

The ornamental design for a reflector unit or the like, as shown.

JOHN C. HAGGART, JR.
